UNITED STATES PATENT OFFICE.

WALTER SKWIERAWSKI, OF MILWAUKEE, WISCONSIN.

BOTTLE WASHER.

Application filed May 2, 1927. Serial No. 188,226.

This invention relates to bottle washers.

Objects of this invention are to provide a novel form of bottle washer in which a simple water motor is employed and associated with means to divert a portion of the water and pass it upwardly through a revolving stem and project the upwardly passing water in the form of one or more streams into the rapidly rotating brush so that while the bottle is actually being internally brushed, it is also being flushed with a continuous stream of fresh water, thus permitting the most thorough and rapid cleaning of the bottles.

Further objects are to provide a bottle washer which may be very cheaply constructed, which has a small number of parts, and which is so made that it may be placed in a sink or tub and readily attached to any suitable source of water under pressure, such as a spigot for instance.

An embodiment of the invention is shown in the accompanying drawings in which:

Figure 1 is a vertical elevation primarily in section showing the device as it stands when in use;

Figure 2 is a sectional view to an enlarged scale on the line 2-2 of Figure 1;

Figure 3 is a sectional view to an enlarged scale on the line 3-3 of Figure 1.

Referring to the drawings, it will be seen that the device comprises a casing 1 preferably cast as a single unit and supported by a standard or base 2. The base 2 is provided with supporting feet 3 which may be of rubber or other material to prevent marring the enamel surface of the sink, as indicated by the reference character 4. The casing is hollow and houses a rotor 5 which

is rigidly connected to a tubular shaft 6. The rotor is provided with a plurality of curved vanes, as may be seen particularly from Figure 2, which slope downwardly. The casing is provided with an inlet portion

7 upon which a hose 8 is received. This inlet portion is provided with a relatively large aperture 9 which terminates in a constricted jet aperture or nozzle aperture 10. As may be seen from Figure 2, the nozzle aperture or jet aperture 10 is arranged off center so that it strikes approximately the middle portion of the blades, as they are exposed to the stream and thus imparts rotary motion to the motor or paddle wheel. The

curved vanes prevent the immediate dis-

charge of the water until a large amount of the energy in the flowing stream has been extracted.

The standard or support 2 is provided with an enlarged hollow portion providing a cavity 11 which merges into the main cavity of the casing 1 and which is narrowed to a discharge passageway 12. This passageway communicates with a relatively large discharge space 13, and it is to be noted from Figure 1, that the legs space the base up a sufficient distance from the bottom of the sink to permit free discharge of the water without surging or squirting.

It is to be noted that the tubular shaft 6 is carried in a tubular casing 14 which forms an elongated bearing for such shaft. The tubular shaft 6 is provided with a collar 15 which rests upon the sleeve 14 and thus supports the rotary portion of the apparatus. The upper end of the rotor 10 is provided with a bearing face 16 which limits the upward motion of the rotary portion of the device.

The upper end of the tubular shaft 6 has secured thereto a member 17 which carries the shank 18 of the brush 19. This shank is formed preferably of twisted wire and is retained in the member 17 or cap by means of a pin 20 which is passed through the loop of the twisted wire 18. Further, the member 17 is crimped or bent so that it is slightly flattened, as shown in Figure 3, to further grip the twisted wire shank 18.

It is to be noted that the member 17 is not completely flattened but that it provides a pair of discharge apertures 21 which communicate with the interior of the tubular shaft 6.

When the device is in use the water passes upwardly through the hollow stem or spindle 6 and is projected into the rapidly rotating brush, thus furnishing a continuous stream of water internally of the bottle while the interior of the bottle is being rapidly brushed and freed of adherent material. The constricted portion 12 in the standard or support 2 insures the discharge of some of the water upwardly through the hollow spindle or tubular shaft 6.

It is to be noted also that the casing 1 may be very rigidly secured to the base portion 2 by the construction illustrated in Figure 1. For example, the base is provided with an upstanding flange 22 which

fits within the interior of the casing and is provided with an outwardly projecting flange 23 upon which the bottom of the casing rests. Screws 24 pass through the flange 23 and into the casing and thus retain the parts against separation.

Although the invention has been described in considerable detail, such description is intended as illustrative rather than limiting 10 as the invention may be variously embodied and as the scope of such invention is to be determined as claimed.

I claim:

1. A bottle washer comprising a casing 15 having a base provided with a constricted discharge aperture, said casing having a pipe receiving portion provided with an inlet aperture, a rotor mounted adjacent said inlet aperture and positioned within 20 said casing and spaced above the lower portion of said casing, a hollow spindle rigidly attached to said rotor and projecting upwardly from said casing, means carried by 25 said spindle for preventing downward motion thereof, and a brush provided with a shank attached to the upper end of said spindle, said spindle having a discharge portion located immediately adjacent said brush, said casing converging towards its lower end

and having a base provided with a discharge 30 aperture.

2. A bottle washer comprising a casing of cylindrical contour and having an inlet aperture entering through its cylindrical wall and located off center with reference to the axis 35 of such cylindrical wall, a base for supporting said casing having a discharge aperture and having supporting feet for spacing said base from a support, a pipe carried by said casing and communicating with said inlet 40 aperture, a rotor mounted within said casing, a hollow spindle rigidly secured to said rotor and projecting upwardly through said casing, a sleeve rigidly carried by said casing and furnishing an elongated bearing for 45 said hollow spindle, a collar carried by said spindle and resting upon the upper end of said sleeve, and a brush carried by the upper end of said hollow spindle, said hollow spindle having a discharge portion adjacent 50 said brush for projecting a stream of water into said revolving brush.

In testimony that I claim the foregoing I have hereunto set my hand at Milwaukee, 55 in the county of Milwaukee and State of Wisconsin.

WALTER SKWIERAWSKI.
